[57] **CLAIM**

The ornamental design for a locking rotatable storage base for business equipment, as shown and described.

DESCRIPTION

FIG. 1 is a perspective view of a locking rotatable storage base for business equipment incorporating my new design;

FIG. 2 is a top view of the base of FIG. 1;

FIG. 3 is a front view;

FIG. 4 is a left side view, the right side view being a mirror image thereof; and,

FIG. 5 is a rear view.

FIG. 1

FIG. 2

FIG. 3

FIG. 4

FIG. 5
